UNITED STATES PATENT OFFICE.

WILLIAM P. QUENTELL, OF NEW YORK, N. Y.

TYPE-WRITING MACHINE.

SPECIFICATION forming part of Letters Patent No. 611,146, dated September 20, 1898.

Application filed September 16, 1897. Serial No. 651,929. (No model.)

To all whom it may concern:

Be it known that I, WILLIAM P. QUENTELL, a citizen of the United States, residing at New York, in the county and State of New York, 5 have invented new and useful Improvements in Type-Writing Machines, of which the following is a specification.

The object of this invention is to obtain a type-writing machine capable of being 10 cheaply made; and the invention resides in the novel features of construction set forth in the following specification and claims and illustrated in the annexed drawings, in which—

15 Figure 1 is a plan view of the machine with the paper-roller sectioned off. Fig. 2 is a section along the line $x-x$, Fig. 1. Fig. 3 shows a key-guiding plate. Fig. 4 is a detail view of a type-segment-actuating lever and adjacent parts. Fig. 5 is a section along the line $y-y'$, Fig. 2. Fig. 6 shows the carriage in side elevation and in printing position. Fig. 7 is a section along the line $y-y'$, Fig. 2. Fig. 8 is an enlarged detail view of the paper-roller or 20 platen-carrier and supporting devices and of the lever mechanism which prevents the paper-carriage touching the paper to the type when the spacing-key is actuated.

A base or support 1 by suitable risers 2, 25 Fig. 2, carries a rod or fulcrum 3 for the keys or levers 4 5. The lever-arms 4 are provided with the finger-buttons 6, and the lever or key arms 5 are engaged by restoring-springs 7, which return the keys when released, as 30 known. From base 1 extend risers 8, carrying a guide or slotted plate 9 for guiding or steadyng the keys. In the drawings are shown two sets of keys, one set being on each 35 side of the median line $x-x$; but the explanation of one key-set will explain the other.

Under each key-set extends an arm or cross-bar 10 of a lever 11, having its fulcrum 12 at a suitable base part 13. As seen in Figs. 1 and 4, the levers 11 can be steadied by having 40 their fulcrum parts 14 doubled or bail-shaped. Each such lever 11 may for convenience of description be called a "main" or "carrying" lever, carrying the fulcrum 15 of what may be called a "secondary" lever 16 17. The secondary-lever arm 16 by means of a lug or engaging part 18 engages or lifts the lever 11. Said lever-arm 16 has a stud or fastening 19,

to which is engaged a spring 20, secured to a suitable fixed point or arm, as 21, Fig. 2, on the machine-base. The spring 20 drawing or 55 moving lever-arm 16 to carry the lug 18 to the lever 11, such spring 20 will lift or return the lever 11 when the parts are free.

The lever-arm 17 has a slot-and-pin connection 22 and 23, Fig. 4, with an arm 24 of lever 24 25, fulcrumed at 26. Of course the pin 22, which is shown on lever-arm 17, might be placed on lever-arm 24 and the lever-arm 17 be slotted instead of the lever-arm 24. Such changes are obvious; as any suitable 65 loose connection between the lever-arms 17 and 24 can be made to answer.

The lever-arm 25 rotates the type wheel or segment. This arm 25 engages a shoulder 27 on a disk 28, Fig. 5, and said disk 28 is fixed to shaft 32, to which shaft is also fixed a plate 29, Figs. 2 and 5, which by arm 30 engages the type-wheel or segment 31, mounted loosely on shaft 32. The disk 28 thus actuates the type-wheel, since when a lever 24 25 swings 70 it engages one or another of the shoulders 27 and rotates disk 28, which rotates the shaft 32 and plate 29 with arm 30 and type-segment 31. The disk 28 has oppositely-located shoulders 27 for the engagement of the respective 75 levers or arms 25 as the wheel is to be rotated in one direction or another.

The type-wheel 31 is mounted on shaft 32, and the rotation of said wheel is suitably arrested by an arm or stop 33. This stop 33, 85 like disk 28, is fixed to shaft 32, and when the machine is at rest this arm 33 lies between the key-sets, as seen in Fig. 1. In mentioning type-wheel a type-segment is of course also naturally understood or included.

A depression of a key-arm 4 depresses the corresponding lever 11, carrying down the secondary-lever fulcrum 15, as also said secondary lever 16 17, against the resistance or tension of spring 20, and such descending 90 lever 16 17 by the stud or joint 22 23 swings the lever 24 25, so as to rotate the type-wheel and swing arm 33 to carry its free end 34 toward the depressed key-arm. This free end 34, striking such depressed key-arm, is arrested, together with the type-wheel, and as a key-arm is depressed which is more or less removed from the median line $x-x$ the arm 33 and type-wheel 31 rotate more or less be-

fore being arrested. Naturally the arrangement of characters or type on the wheel is such that when the arm 33 comes to stop against a depressed key-arm the character which has been turned or carried by the wheel to the printing-point corresponds to that key-arm 4 or button 6 which has been depressed. The key-arms 4 are normally so high that the arm or stop 33 can swing past under the key-arms, as seen in Fig. 2, and by suitably bending or thickening the free end 34 of arms 33, Fig. 2, such free end 34 will be prevented from missing or slipping past a depressed key or losing its engagement with such key until released or until the printing is completed. The stop-arm 33 and disk 28 being separately fixed or secured to shaft 32, the arm 33 can be set to correspond to the higher or lower level at which the keys may be set in different machines, and the disk 28 can be set for proper engagement by the lever-arm 25 or by the free end of such arm. After the arm 33, with the type-wheel, is arrested by a depressed key such key continues its downward travel to effect the printing stroke, as presently explained. The type-wheel having been arrested, as stated, the disk 28 holds the lever 25 24 against further motion; but the secondary-lever fulcrum 15 continuing to descend with the main lever 11 and the slot 23 and pin 22 forming a loose joint, which allows play, or the stud or stop 22 being free to play in such slot, the secondary lever swings about such stop or stud 22 during this further descent of fulcrum 15, so as to swing the lever arm 16 downward against the tension of lifting-spring 20. This secondary lever 16 17, while normally a first-class lever with fulcrum at 15, may, during this further descent of fulcrum 15, while lever 25 24 is fixed, be considered as temporarily a third-class lever with the fulcrum at 22, the power-point at 15, and the resistance-point at 19 or at the spring 20. On the release of the depressed key the tension of spring 20 draws the lug 18 on lever-arm 16 against the main lever 11 with such force as to raise or return the main lever to its position of rest.

The disk 28 in addition to the shoulders 27, Fig. 5, has also the shoulders 35, and when a lever-arm 25 is rotating the type-wheel said arm 25 engages or lies between said shoulders 27 and 35, and the disk and wheel are rotated one way or another by said lever swinging back and forward. When the parts are at rest, the lever-arms 25 lie clear of and forward of said shoulders 27 and 35 and alongside a tailpiece 28', Figs. 5 and 6, extending forward from said disk 28, and in this position neither lever-arm 25 offers any obstruction to the other lever-arm actuating the type-wheel; but said lever-arms 25, both lying against tail 28', act as a centering device for holding stop-arm 33 at the starting-point or median line. When the tail 28' lies in normal or central position, as shown in Fig. 5, either lever-arm 25, when swinging

backward, will clear or move past tail 28' to strike the corresponding shoulder 27. Say, for example, the right-hand lever 25 in Fig. 5 swings backward, and, striking its shoulder 27, swings the type or printing face of wheel 31 to the left and the tail 28' to the right. By this right-hand swing of tail 28' the shoulder 35 on the right is carried to the right, so that when the right-hand lever 25 now returns forward it will strike this right-hand shoulder 35, so as to return the tail 28' to the median position, where this right-hand lever 25 can clear such right-hand shoulder 35 to return to rest.

The paper roller or platen 37, Fig. 2, together with guide rod or roller 38 for the sheet or paper 39, are journaled or mounted in a carriage 40, the foot 41 of which travels in a suitable way or guide 42 on arms 43, which are movably supported, as by pivots 44, so that they can swing the platen, with the sheet 39, toward the type or segment for executing a stroke or print. The arms 43 have a cross-bar 45, Figs. 1, 2 and 6, extending across the machine underneath or into engagement with the main levers 11, so that as one or another of the latter is depressed it descends onto the cross-bar to swing the arms 43 about the pivot or fulcrum 44 and carry or swing the platen to the type-segment. The carriage 40 or its foot 41 carries a feed-rack 46, Fig. 7.

Pivoted to the way 42 at 47 is a swinging plate 48, having at its rear a lip or turned-up shoulder 49. Pivoted or fulcrumed to this plate at 50 is a pawl 51 52, and as this pawl swings about pivot 50 in either direction such swings are limited by either pawl-arm 51 or 52 striking this shoulder or stop 49. The spring 53 holds the plate 48 toward the rack 46 and the spring 54 holds the pawl toward such rack. The spring 53 extends from the way or base 42 to the plate 48 and the spring 54 extends from this plate to the pawl.

An arm 55, Fig. 2, is suitably fixed to the base 1, and as the platen-carriage swings or falls back or away from the type-segment the plate 48, Fig. 7, or its nose 56 comes to rest against the arm 55, and the plate is swung against the tension of spring 53 to carry the pawl away from the rack 46. The spring 54 then swings the pawl to bring its arm 51 to rest against the stop 49, this swing of the pawl being sufficient to bring the pawl-arm 52 into position to take into the next succeeding tooth of rack 46, when the plate 48 again swings toward the rack upon the platen, moving toward the type. The spring 53 is powerful enough to not only swing the plate 48, with the pawl, to the rack, but also to swing pawl-arm 52 to the stop 49 against the resistance of spring 54. This swing of pawl-arm 52 to the stop 49 after said pawl has taken hold of the rack 46 causes the rack, with the carriage, to be fed along for one step or tooth, and when the spring 54 has drawn the pawl to the rack and the pawl-arm 52 is braced or stopped against the stop 49

the pawl holds the rack, with the carriage and paper-roller, against motion on the way 42.

The sides of the carriage, as seen, form bearings or supports for the roller 37, and 5 these sides, as well as the carriage-front 57, Fig. 2, rise from rack 46. This front has cut-out portions bent to form tongues or guides 58 for leading or holding the paper 39 about the roller. The sides are cut through 10 rear edge, as seen at 59, Fig. 2, such cuts or slots allowing the roller to be slipped into and removed from the carriage. Springs 60, suitably applied, hold the roller toward the carriage-front.

15 The ribbon-spools 61 have ratchets 62, Fig. 1, for the engagement of pawl 63, pivoted at 64. Springs 65 normally hold the pawls to the ratchet. One pawl or another can be locked out of action, as by a suitable peg or 20 other holding device, and in Fig. 1 the pawl 63 at the left-hand side is shown out of action, while the opposite pawl engages its ratchet 62. The pawls 63 have their pivots 64, carried by arms 66 67, swinging about the 25 shafts of spools 61.

When the carriage swings forward, the way or track 42 strikes the tail or end 66 of the arms 66 67 to swing the latter and shift the active pawl 63 one tooth along the respective 30 ratchet 62. On the return of the carriage and of the arm 66 67 with the active pawl the corresponding spool 61 is turned for feeding the ink-ribbon. The springs 65 are arranged not only to hold the pawls 63 in action, but also 35 to return the arms 66 67.

A spacing-lever 68 69, Fig. 1, passes under or clear of the levers 10 11, so that the depression of this lever will not actuate the type-wheel, but said spacing-lever, engaging 40 cross-bar 45, will swing the carriage or the arms 43 sufficiently to clear plate 48 from arm 55, but not so far as to drive the paper 39 to the type. The plate 48, being cleared from arm 55 and then being returned to rest against 45 said arm, will vibrate the pawl 51 52 to feed the carriage the distance of one rack-tooth, as already stated.

The type-segment with two or more rows of type, as required, can be lifted by one or 50 more levers 70, Figs. 1 and 6, to bring lower type-rows into action.

A hammer 71, Figs. 2, 6, and 7, is carried by an arm or gooseneck 72, fixed to way 42. When the carriage swings or flies to the type, 55 the hammer-head 71 presses the printing-point of the paper or sheet 39 to contact with the required type.

The spacing lever or key 69 engages a cross bar or rod 73, connecting the arms 74 of levers 74 75, fulcrumed at 76, and when the spacing-key is depressed the lever-arms 75 are thrown toward the way 42 to prevent the paper-carriage striking or touching the paper to the type. As seen in Fig. 8, each lever 74 55 75 is somewhat of the shape of a bell-crank lever, so bent that when the arm 74 swings

downward the arm 75 swings backward or toward the way 42.

To obtain a clear impression, the hammer or head 71 can be advantageously faced with 70 a soft rubber cap or like soft material, as by slipping a rubber tube or band over such hammer-head. At the same time the stroke of the hammer can be further softened by the paper 39 being doubled between the hammer and the type during the greater period of writing, as seen in Fig. 2.

The levers 70 lift the type-wheel 31 by means of the angular arm 77 78, Fig. 6, the branch 78 of said arm engaging the grooved 80 metallic hub 79, Fig. 2, to which the type-wheel is secured or about which hub such wheel is fixed, such wheel being hollow and having its top, bottom, and periphery made of light material—as, for example, one piece 85 of hard rubber. The branch 77 of said arm passes through upper and lower guide-plates 80 and 80' and rests on the levers 70. Set or stop screws 81, Fig. 6, variously adjusted in the lower guide-plate 80', limit the play of 90 each lever 70, so that as one or another of the levers 70 is depressed the wheel is shifted to bring the middle or lower row of type to the printing-line. Normally the top row of type is the one used, such top row being at 95 the printing-line when the levers 70 are at rest. A set-screw or adjustable rest 82 limits the drop or descent of branch 77 or of the type-wheel as required for bringing the top row of type into action. A spring 83 tends 100 to return the arm 77 78 when the levers 70 are free.

The type-wheel 31 slides or moves longitudinally on the shaft 32, while the latter has no longitudinal motion. Rotation of the 105 shaft 32, as already seen, is imparted to the type-wheel by the plate 29 and arm 30. The plate 29 has its periphery provided with or formed into concentrically arranged Y-shaped guiding-slots, as seen in Fig. 5. A 110 yielding or spring arm or lever 84, Fig. 2, is placed in the path of the carriage-way 42, so that as the way swings toward the type the lever or lock 84 is brought into engagement with one or another of the slots to set or lock 115 the plate 29 and type-wheel with the required type in proper position for a clear print.

The slotted plate 9 by having a second slotted plate or plates 9', Fig. 3, adjustably secured thereto, as by screw-and-slot connection, can have the width or size of its slots or passages regulated to accurately fit or guide the keys. Supposing the slots in plate 9 are so wide as to allow the front ends of arms 4 to wobble or rattle, by setting plate 125 9' laterally a sufficient distance such lateral play or excessive looseness of arms 4 can be remedied. Of course plate 9' must not be set so tight against arms 4 as to bind or interfere with the proper play or function of 130 the keys.

The top guide-plate 80, as seen in Fig. 1,

extends across the machine and has depressions or cut-outs back of the points or shoulders 85. Should either of the arms 66 or pawls 63 swing to a greater extent than the space of one of the teeth of ratchet 62, the respective shoulder 85 on such excessive forward swing will lift pawl 63 away or clear from the ratchet, and the pawl 63 on its return or backward swing will only take into the ratchet 62 at that point of the travel of the pawl as to cause the spool 61 to rotate the space of one ratchet-tooth.

The ink-ribbon, as known, can suitably extend from one spool to another, being suitably held before the faces of the type.

The shaft 32 can be suitably steadied or held to base 1 by a screw 86, Fig. 6, set into a suitable part or riser 87 of the machine or of the plate 80. To keep the paper 39 in position or from falling forward, arms 88, Fig. 2, can be placed on the way 42 on each side of and close to the printing-point. Such arms can be formed from sheet metal.

The front 57 can have a scale stamped or printed directly thereon. In Fig. 9 is shown a piece of front 57 with a scale indicated thereon.

What I claim as new, and desire to secure by Letters Patent, is—

30 1. The combination with a main or carrying lever, of a secondary lever fulcrumed to the main lever and provided with an actuating or lifting spring and lug for such main lever, and with a stud or stop for arresting or holding the secondary lever at one point while leaving the fulcrum of the secondary lever free to move with the main lever substantially as described.

40 2. The combination with a main or carrying lever, of a secondary lever fulcrumed to and made to actuate or lift the main lever, a type-carrier and connections between such type-carrier and the secondary lever, an actuating spring or mechanism made to engage the secondary lever at one side of its fulcrum, and a stop or arm made to engage the secondary lever at the other side of its fulcrum substantially as described.

50 3. A main or carrying lever, combined with a secondary lever fulcrumed to the main lever, a type-carrier and connections between such type-carrier and the secondary lever, a spring made to engage one arm of the secondary lever for holding said arm in engagement with the main lever, and a stop made to engage the other arm of the secondary lever substantially as described.

60 4. A main or carrying lever and a first-class lever fulcrumed to the main lever, one arm of the first-class lever being provided with a stop or stud and its other arm being made to engage the main lever and being provided with a lifting or actuating spring, an arm for engaging or arresting the stop and a type-carrier and connections between such type-carrier and the first-class lever substantially as described.

5. A main or carrying lever and a first-class lever fulcrumed to the main lever, one arm of the first-class lever being provided with a stop or stud and its other arm being provided with a lug extended under the main lever for supporting or lifting the latter, and a lifting-spring made to engage said first-class lever substantially as described.

75 6. A type-actuating arm or lever, a stop for arresting said lever, a secondary lever connected to the type-actuating lever, a main lever to which the secondary lever is fulcrumed, and a spring connected to the secondary lever, and made to actuate or lift the main and secondary levers substantially as described.

80 7. A type-actuating arm or lever, a stop or arm for arresting said lever, a secondary lever, a main lever to which the secondary lever is fulcrumed and which is engaged or lifted by said secondary lever, and a spring connected to the secondary lever, said type-actuating lever and secondary lever being 90 loosely connected or jointed to one another so as to allow play or motion of main and secondary levers after the type-actuating lever is stopped or arrested substantially as described.

95 8. A type wheel or segment, an actuating-lever for the segment, a stop for said lever and segment, a secondary lever for engaging the type-actuating lever, and a main lever to which the secondary lever is fulcrumed, said 100 main and secondary levers being made to engage or actuate one another and a spring for returning the main and secondary levers substantially as described.

105 9. A type wheel or segment, an actuating-lever for the segment, a secondary lever having one of its arms pivoted directly to the segment-actuating lever, a main lever to which the secondary lever is fulcrumed, a key for actuating the main lever, and an arm or stop 110 made to contact with the key for arresting the segment substantially as described.

110 10. A type wheel or segment, an actuating-lever for the segment, a secondary lever made to engage the actuating-lever, a main lever 115 to which the secondary lever is fulcrumed, a key for actuating the main lever, and an arm or stop above which the key is normally located and into the path of which the key is depressed for arresting the segment substantially as described.

115 11. A series of keys, a main lever having an arm extended under the keys, a type wheel or segment, a segment-actuating lever, a secondary lever fulcrumed to the main lever and 125 made to engage the segment-actuating lever, and a segment stop or arm made to contact with the keys as the latter are depressed so as to arrest the segment at different degrees of rotation substantially as described.

130 12. A series of keys, a main lever having an arm extended under the keys, a type wheel or segment shaft, a segment-actuating lever, a secondary lever fulcrumed to the main le-

ver and made to engage the segment-actuating lever, and a segment stop or arm made to contact with the keys as the latter are depressed so as to arrest the segment at different degrees of rotation, said segment-shaft having shoulders made to engage with the actuating-lever to rotate the segment from and to return the segment to the starting position and hold it at such starting position on the release of the keys substantially as described.

13. A series of keys, a main lever, a type wheel or segment shaft, a segment-actuating lever, a secondary lever fulcrumed to the main lever and made to engage the segment-actuating lever, a returning-spring 20, and a segment stop or arm made to contact with the keys as the latter are depressed so as to arrest the segment at different degrees of rotation, said segment-shaft having shoulders made to engage the actuating-lever to rotate the segment and to return the same to and hold the same at the starting-point.

14. A type-writing machine provided with a paper-carriage, a vibrating way for the carriage, a spacing-key for vibrating the carriage-way, and a lever actuated by said key for arresting the vibration of the carriage substantially as described.

15. A type-wheel combined with a lifting-arm, upper and lower guide-plates for the arm, a returning-spring for the arm, lifting-levers for the arm, stop-screws in the lower guide-plate for regulating the lifting movement, and a supporting-screw adjustably secured under the lifting-arm substantially as described.

16. A paper-roller carriage comprising a rack, sides and front on said rack, journal-slots extended through the back of the sides, a guide-rod above the roller, and springs for pressing said roller against the front, said front having a scale and cut-out portions bent to form guides substantially as described.

17. A type-writing machine provided with a vibrating paper-carriage way, a ribbon-spool, a lever actuated by the way and provided with a pawl for engaging the spool, and a supporting-plate for the spool-shaft, said plate being cut away or shouldered at one point to allow the pawl to engage the spool at such point and to lift the pawl clear of the spool when passing beyond said point substantially as described.

18. A type-writing machine provided with type and with a carriage made to swing toward the type, a spacing-key for actuating the carriage, and a lever actuated by the spacing-key for preventing the carriage from contacting with the type substantially as described.

19. A type-wheel provided with a plurality of type-rows, a shaft on which said wheel is mounted, a stop-arm directly mounted on said shaft, means substantially as described for rotating the wheel, and key-levers made to arrest said stop-arm, said key-levers being non-radiatingly arranged, substantially as described.

20. The combination with a type-wheel, a shaft provided with shoulders, a hammer and a platen, of oppositely-located driving-levers made to engage the shoulders, a lever made to actuate each driving-lever, and a lever made to positively or directly engage and actuate the frame supporting the hammer or platen, and keys or key-levers for actuating the two last-named levers substantially as described.

21. The combination with a type-wheel, a shaft provided with a stop-arm and with shoulders, a hammer and a platen, of oppositely-located driving-levers made to engage the shoulders, a lever made to actuate each driving-lever, a lever made to positively or directly engage and actuate the frame supporting the hammer or platen, and keys or key-levers for actuating the two last-named levers and for directly arresting the stop-arm, substantially as described.

22. The combination with a type-wheel, a shaft provided with a stop-arm and with shoulders, a hammer and a platen, of oppositely-located driving-levers made to engage the shoulders, a lever made to actuate each driving-lever, a lever made to actuate the hammer or platen, and keys or key-levers for actuating the two last-named levers and directly arresting the stop-arm, substantially as described.

In testimony whereof I have hereunto set my hand in the presence of two subscribing witnesses.

WILLIAM P. QUENTELL.
